(57) **CLAIM**

We claim the ornamental design for a cover for portable device, as shown and described.

DESCRIPTION

FIG. 1 is a front perspective view of a cover for portable device showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is another front perspective view thereof shown in an example environment.

The broken lines in the figures depict environmental subject matter and form no part of the claimed design.

The dot-dash broken lines in the figures represent an unclaimed boundary line and form no part of the claimed design.
